HIGH FREQUENCY LOOP TYPE ANTENNA

Robert A. Hampshire, New York, N. Y., assignor
to Federal Telegraph Company, Newark, N. J.,
a corporation of California

Application July 12, 1941, Serial No. 402,099

9 Claims. (Cl. 250—33)

This invention relates to broadcasting antennae and more particularly to high frequency broadcasting antennae of the loop type.

Broadcasting antennae have been proposed in which the antennae elements are each less than a half-wave length long and arranged in the form of a substantially closed periphery. The separate elements are coupled end to end by capacitive coupling and alternate ones of said elements are positively energized by transmission lines coupled at spaced points on either side of the voltage nodal points. Metallic supporting struts are connected to the voltage nodal points of the elements and to the supporting mast. Such types of antennae are illustrated in the copending application to Andrew Alford, Serial No. 358,214, filed September 25, 1940.

This proposed antenna had many advantages such as freedom from insulators in exposed places, and relative simplicity of construction. It was also found to have certain shortcomings. It was found that the radiation pattern is not precisely circular but is slightly stronger in the direction perpendicular to the driven members. This can be substantially overcome by adjusting the capacitive couplings to obtain substantially equal large currents in all the elements. However, with such adjustment the antenna does not present proper impedance to terminate the transmission line. Adjustment of the spacing of the feed line tap improves the impedance match but even with the best adjustment the standing wave ratio is still in the order of 3.5 to 1.

When the loop is adjusted off resonance the current in the parasitic elements is reduced, and some current is present in the supporting struts.

My invention constitutes an improvement on the antennae of the proposed type described above.

It is a principal object of my invention to provide an antenna for broadcasting purposes which is rigid and which may present such an impedance to the feeding line as to require a minimum of external impedance matching.

It is a further object of my invention to provide an antenna which has a substantially uniform radiation characteristic in the plane of the antenna elements.

According to a feature of my invention the desired objects may be accomplished by providing an antenna structure in which the antenna is made of radiant acting elements each being short relative to the operating wave-length. The elements are arranged in the form of a substantially closed periphery and capacitively coupled at their

ends. Each radiant acting element is divided at its center and provided with a parallel transmission line which may act as a support, short circuited at an adjusted position to secure the desired tuning of the loop as a whole, together with the coupling capacities. Energy may be supplied to the loop by a transmission line coupled at a point intermediate the short circuiting bar and the associated radiant acting element of one of the units. A tie line may be provided from this coupling point to alternate ones of the remaining elements so that losses in the elements may be compensated.

A better understanding of my invention and the objects and features thereof may be had from the particular description thereof made with reference to the accompanying drawings in which:

Fig. 1 is a diagrammatic showing illustrating an antenna constructed and fed in accordance with the features of my invention;

Fig. 2 is a diagrammatic showing of a preferred antenna arrangement in accordance with my invention;

Fig. 3 is a plan view of a practical working embodiment of an antenna constructed in accordance with my invention;

Fig. 4 is a side elevation of a portion of the antenna shown in Fig. 3 to illustrate the construction; and

Fig. 5 is an actual experimental radiation pattern derived from an antenna constructed in accordance with my invention.

In Fig. 1 is shown an antenna arrangement formed of four radiant acting members, 1, 2, 3 and 4, that is, members which may be used either for transmission or reception of radio waves. These members are shown supported at their midpoints by bars 5, 6, 7 and 8 from a central mast 9. The radiant acting members 1, 2, 3 and 4 are capacitively coupled together at their ends by condensers 11, 12, 13, 14. A translating device 15 which may be either a transmitter or a receiver is connected by a transmission line 16 to spaced points 17 on radiant acting member 2. A substantially half-wave length line 18 is provided for interconnecting points 17 and corresponding points 19 on radiant acting member 4. A pair of condensers 20, 21 may be provided in transmission line 16 at a point adjacent the radiant acting member in order to provide the impedance match between the transmission line and the antenna.

It has been found that when an antenna unit such as shown in Fig. 1 is energized from one side only, a radiation pattern equal in all directions in the plane of the antenna is not produced, the

radiation diagram being displaced in the direction toward the directly fed member. This dissymmetry is marked even when the capacitive coupling members are adjusted so that substantially equal currents may be present in all the antenna members. The exact reason for this inequality is not precisely known, but an explanation of this phenomenon may be substantially as follows:

While energy is readily propagated around the loop due to the capacitive coupling, there is apparently an attenuation of energy in all of the members due to radiation from the separate members. Simultaneously, there is a super-imposed energizing of the member diametrically opposite the fed member. This energizing causes a current in this opposite member which is not precisely in phase with the current in the fed member. Such phase shift in currents may then be considered to produce the unsymmetrical radiation pattern.

In order to correct the pattern it has been found that a section of transmission line substantially a half-wave length long may be connected from the tapping points on the fed member to corresponding points on the diametrically opposite member. This line may equally well be made other lengths so long as it is electrically equivalent to a half-wave length or odd multiple thereof. This tie-line then delivers power to the diametrically opposite member in an amount sufficient to correct the loss due to attenuation. With this arrangement the radiation in all directions in the plane of the antenna members is substantially equal. It has been found that this tie-line carries a very small current compared to the current flowing in the radiant acting member.

The impedance match between the transmission line 16 and the antenna is very poor for ordinary spaced conductor arrangements. In order to reduce this mismatch, condensers such as 20, 21 may be provided in the transmission line. This has been found to reduce the mismatch so that the line can be matched completely to the antenna.

The arrangement of Fig. 1 is unsatisfactory in some respects due to the fact that the matching condensers must be mounted at a point adjacent the antenna and therefore, are generally relatively inaccessible. Accordingly, special precautions must be taken in order to assure freedom from leakage of these condensers at the time they are installed, since atmospheric conditions or sleet formations might otherwise impair their operation. Such constructions are generally cumbersome and are not easily arranged on the mast portion arrangement.

The difficulties caused by the use of the condensers may be partially overcome by utilizing an antenna construction such as illustrated in Fig. 2. In this arrangement each of the radiant acting members is divided at its midpoint to form two parts 1A, 1B, 2A, 2B, 3A, 3B, 4A, 4B, the members being capacitively coupled by condensers 11, 12, 13, 14. Between each of the parts 1A, 1B, 2A, 2B, 3A, 3B, 4A, 4B, are arranged transmission line sections 5A, 6A, 7A, 8A, each terminated by short circuiting bars 31, 32, 33 and 34. These short circuiting bars are adjusted to provide a suitable terminating impedance for the transmission line feeding the loop, although the adjustment of the short circuiting bars may not, for all constructions of such a loop, give a perfect impedance match to the transmission line. The mismatch will never-

theless be small compared with that obtained without this type of construction. The difficulties of providing a complete impedance match may, therefore, be greatly alleviated.

5 The translating device 15 is then coupled by transmission line 16 to points 17 arranged along the short circuiting section at a point dependent upon the desired impedance. In most practical constructions it has been found that the coupling points 17 should generally be substantially at the junction point of the radiant acting parts and the transmission line section, since the short circuited section generally is not sufficient to produce an impedance match, and consequently 10 all its impedance must be used.

15 In Figs. 3 and 4, is shown an actual practical construction of a loop embodying the features shown diagrammatically in Fig. 2. In this type of loop it is generally desirable that the antenna units be self-supporting and that they be arranged so that they may be fastened directly to a metal mast or support without the necessity of providing insulators. Accordingly, members 1A, 1B, 2A, 2B, 3A, 3B, 4A, 4B, are made 20 of metallic pipe, fastened directly to a split collar 40 which clamps directly onto the mast. Since parts 1A, 1B, 2A, 2B, 3A, 3B, 4A, 4B, occur substantially at a voltage node, they need not be provided with insulation.

25 30 The condenser elements are formed of capacitive plates 11A, 11B, 12A, 12B, 13A, 13B, 14A, 14B, preferably formed as parallel discs mounted on rods 11C, 11D, 12C, 12D, 13C, 13D, 14C, 14D, 35 adjustably arranged within hollow members 1B, 2A. These plates may be clamped in adjusted position to secure the proper tuning of the loop. The short circuiting bars are made in the form of adjustable clamps 31A, 32A, 33A, 34A, as shown.

40 45 In an actual construction of a loop designed to operate at 46 megacycles the dimension from side to side of the loop is 72", the diameter of the members 1A, 1B, is approximately 2½", the plates 11A, 11B are about 14" in diameter, the spacing between these plates is about 8". It has been found that the loop can be made quite different in size. As the loop is made larger, the radiation pattern departs from circularity and tends to become square. As the loop is made 50 smaller, the radiation pattern remains circular but the resonant characteristics of the loop become similar to those of a high quality tuned circuit. It is preferred, therefore, to have the dimensions from side to side of the loop between 55 80 and 110 electrical degrees.

55 In Fig. 5 is shown a curve of a radiation pattern produced by experimental measurements of the radiation from a loop in accordance with my invention. This loop was made with the 60 same wave lengths proportions as those given for the particular example outlined above, but scaled down for operation at 150 megacycles.

65 While I have described the principal features of my invention in connection with the preferred form of the loop, it is to be understood that departures may be made therefrom, without departing from the spirit of my invention. For example, the loop need not be made square in form but the members may be bent into any desired regular geometrical configuration. Furthermore, all points of support occur at substantial voltage nodes, so that direct connections can be made without producing large currents in the supporting structure and consequent 70 losses. Also, although it is preferable to make 75

the antenna self-supporting the principles of my invention apply as well to any antenna structure even if separate supporting means are required for the radiated members.

What is claimed is:

1. An antenna unit comprising four radiant acting members each being short with respect to a half wavelength at the operating frequency, said members being arranged to form a substantially closed periphery, capacitive reactance means coupling together adjacent ends of said members, a translating device, a transmission line interconnecting said translating device and one of said radiant acting members, and a substantially half wavelength line interconnecting the junction points of said transmission line and said one radiant acting member and corresponding points on the oppositely positioned member.

2. An antenna unit according to claim 1 further comprising capacitive reactance means in series with said transmission line adjacent said one radiant acting member.

3. An antenna unit according to claim 1 in which said radiant acting members are divided substantially at their mid-points into two parts further comprising a short circuited transmission line section connecting together said two parts.

4. An antenna unit comprising a plurality of radiant acting members each being short with respect to a half wavelength at the operating frequency, said members being arranged in the form of a substantially closed periphery, capacitive reactance means coupling together adjacent ends of said members, each radiant acting member being formed of a pair of substantially equal length elements, a section of parallel transmission line extending from the adjacent ends of each of said pairs of elements, a short-circuiting bar arranged at a predetermined point along each of said transmission line sections, a translating device, and means for coupling said translating device to a point on one of said transmission line

sections intermediate said elements and said short-circuiting bar.

5. An antenna unit according to claim 4 wherein in said transmission line sections are made of relatively heavy conductive material, whereby they may serve to support said elements, further comprising a metallic supporting structure, and means for rigidly fixing said transmission line sections to said metallic supporting structure.

10 6. An antenna unit according to claim 4 further comprising conductive transmission means interconnecting said intermediate point and a similar intermediate point on another of said transmission line sections.

15 7. An antenna unit comprising a four of radiant acting members each being short with respect to a half wavelength at the operating frequency, said members being arranged in the form of a substantially closed periphery, capacitive reactance means coupling together adjacent ends of said members, each radiant acting member being formed of a pair of substantially equal length elements, section of parallel transmission line extending from the adjacent ends of each of said pairs of elements, a short circuiting bar arranged at a predetermined point along each of said transmission line sections, a translating device, and means for coupling said translating device to a point on one of said transmission line sections intermediate said elements and said short circuiting bar.

20 8. An antenna unit according to claim 7 further comprising a conductive transmission means interconnecting said intermediate point and a similar intermediate point on the oppositely positioned transmission line section.

25 9. An antenna unit according to claim 7 further comprising capacitive reactance means in series with said transmission line adjacent said one radiant acting member.

40 ROBERT A. HAMPSHIRE.
